CLAIM

The ornamental design for a shelf, as shown and described.

DESCRIPTION

FIG. 1 is a perspective view of a shelf, showing my new design;

FIG. 2 is a top plan view;

FIG. 3 is a side elevational view, the opposite side being a mirror image thereof;

FIG. 4 is an end elevational view, the opposite end being a mirror image thereof;

FIG. 5 is a cross-sectional view taken along line 5—5 in FIG. 2;

FIG. 6 is an enlarged fragmentary view of the side shown in FIG. 3; and,

FIG. 7 is an enlarged fragmentary view of the end shown in FIG. 3.

FIG. 1 has been drawn on a reduced scale with respect to FIGS. 2-5.

The characteristic feature of the design resides in the shape and configuration of the support trusses of the shelving frame.
